WATER COLUMN DISPLACEMENT WEIGHT

Filed July 23, 1932

UNITED STATES PATENT OFFICE

2,028,858

WATER COLUMN DISPLACEMENT
WEIGHT

Alfred L. Aicher, Philadelphia, Pa., assignor to
Yarnall-Waring Company, Philadelphia, Pa., a
corporation of Pennsylvania

Application July 23, 1932, Serial No. 624,314

2 Claims. (Cl. 73—82)

The invention relates to water columns for boilers or the like with particular reference to water columns having metal weight or water displacement equipment together operating as a "float" to secure automatic operation that may be continuous, as to show a gauge reading at a point lower than the water level of the boiler, or that may be operative in the event of an undesirably abnormal water level, either high or low.

While intended for any use to which it is adapted, the invention is believed to have a wide and perhaps its widest and best application in water column structure and the like, of the types disclosed in United States Patent, No. 1,833,630, granted Nov. 24, 1931, upon application of David Robert Yarnall, for "Mercoil alarm and indicator" and United States Patent No. 1,933,132 upon application of David Robert Yarnall, for "Indicator for water level" and the invention has therefore been illustrated by figures selected from these cases, modified to illustrate the new invention.

The metal weight or displacement mechanism of the character indicated normally includes oppositely acting members, one high and one low, the mechanism being moved by weight action at one of the members, then partially submerged in water (or other liquid medium herein conventionally called water) and extending upward above the line of submergence into steam (or other vapor or gas herein conventionally called steam).

The weight of the partially submerged member less its buoyant force (the weight of liquid displaced by the submerged portion of the member) is counterbalanced by an upward pull from the other member which at this time may be wholly submerged or wholly above the level of the liquid effectively floating the first member.

A usual characteristic of metal weights or displacement members of the character indicated and operative when partially submerged by change in the elevation of the water level is a safety requirement that they be solid rather than hollow and that they present a noncorrodible surface to the hot steam and hot water.

The latter requirement has resulted in the water displacement members (effectively weights) being usually made of cast iron rather than the lighter aluminum for example, which reacts with the hot water and hot steam under conditions frequently met in service.

A purpose of the invention is to lighten a solid metal displacement member or weight.

A further purpose is to obtain increased power through the weights by adopting a lighter metal fill such as aluminum in an iron shell, thereby making the weights deeper than would be the depth of solid iron weights.

A further purpose is to form a weight of the character indicated by surrounding a relatively specifically light interior comprising a metal deleteriously reactive to hot water or steam with an exterior shell of material nonreactive to hot water or steam.

A further purpose is to fill a metal shell of cast iron or the like with aluminum or other relatively light material.

A further purpose is to shield an aluminum weight from contact with steam or hot water by surrounding it with a shell nonreactive to steam or hot water.

Further purposes will appear in the specification and in the claims.

I have elected to show two only of the different forms of my invention, selecting forms however that are practical and efficient in operation and which well illustrate the principles involved.

Figure 1 is a side elevation of a device that includes weight structure embodying the present invention, the figure corresponding to Figure 1 of said Patent No. 1,833,630, except that the counter-acting high and low members, respectively weights at abnormally high and at abnormally low water levels, have been modified to embody the present invention.

Figure 2 is an elevation, partly in section, showing a water glass at the water level, and a plain auxiliary water glass below the water level and operated by a weight of the present invention, the view corresponding to Figure 1 of Patent No. 1,933,132, above referred to, except that the weight has been modified to embody the present invention.

Like numerals refer to like parts in all figures.

Describing in illustration and not in limitation and referring to the drawing:—

In the structure shown in Figure 1 a water column chamber 10 connects to a boiler, not shown, at lower and upper flange connections 11 and 12 respectively, the lower connection 11 being well below and the upper connection 12 well above the level of the surface of the water in the boiler.

The normal water level is indicated at 13, mid-

55

way between the opposing upper and lower displacement weights 14 and 15 respectively.

5 The weights 14 and 15 operate against one another upon a valve member 16, the difference in the effective downward pull of the weight members being used by any suitable connections, not shown, to control the position of the valve.

10 Normally the lower weight is wholly submerged and the upper weight wholly above the surface of the water and the weight members have such size and weight relations and such mechanical linkages to the valve 16 that the valve is then maintained closed, the effective downward pull of the lower weight (normally wholly submerged) 15 being then less than the downward pull of the upper weight (normally wholly above the water level) and the greater pull of the upper weight being then used to hold the valve shut.

15 If the water in the chamber 10 becomes unduly high the upper weight becomes wholly or partially submerged and there is a resultant upward force of buoyancy upon the upper weight which makes the downward pull of the upper weight less than that of the lower weight and the 20 greater pull exerted by the lower weight then opens the valve.

25 In the same way if the water level becomes unduly low the lower weight is wholly or partially out of the water and the resultant increase in the downward pull of the lower weight acts in the same direction as before, making the lower weight again effective to open the valve.

30 With normal water levels, the upper weight is predominate to an extent sufficient to hold the valve shut and with either abnormally high or abnormally low water a change in a buoyant force upon one weight or the other makes the lower weight predominate to an extent sufficient to open the valve member.

35 40 The operating force for either abnormally high or abnormally low water is the difference between the downward pull of one weight as compared to that of the other, which is determined by the change in water displacement, and therefore is 45 determined by the selected dimensions of the weights and is obviously independent of the magnitude of the individual downward pulls.

45 While this is true, I find that the sensitiveness of the mechanism, for a given difference between 50 the downward pulls, is very greatly affected by changes in the actual magnitudes of the pulls, and that the same difference of pull will react much more sensitively if the pulls themselves are relatively small than if they are relatively large.

55 This is doubtless incident to the fact that friction of the mechanism varies directly with the magnitudes of the downward pulls rather than with the difference between the pulls.

60 In accord with the present invention, the displacement weights 14 and 15 are made of the same size as before but are made relatively light by providing them with an interior of aluminum.

65 Safety requirements forbid making the weights hollow and the chemical characteristics of aluminum forbid the use of all-aluminum displacement weights in that hot water and steam under the service conditions of the displacement weights may deleteriously react with aluminum.

70 75 As a result the displacement weights have in the past been made of solid cast iron, preferably of special composition to reduce to a minimum any deleterious reaction with the water and steam, and the sensitiveness to change has, as a result, been less than I find can readily be ob-

tained by the use of weights embodying the present invention.

I provide a mere shell exterior 18 or 18' of cast iron and fill the interior 19 or 19' with aluminum, preferably initially molten, suitably closing the pour hole with a nonreactive material. I thus obtain a displacement weight that is for a given displacement far lighter than the weights of the prior art but that maintains the nonreactive surface of the iron in contact with the water and 10 steam of the chamber.

As illustrated, the lower weight 15 has been cast as a thin iron shell with a pour hole at 20. The interior of the shell has then been filled with aluminum and the opening at 20 closed by 15 threading the weight upon the lower end of the supporting rod 21.

20 The upper displacement weight has been cast as a hollow shell exterior 18' having a central perforation 22 to freely pass the rod 21 and provided with pour holes at 23 and 24, finally closed after the interior 19' has been filled with the initially molten aluminum by threaded connection with the lower ends of the rods 25 that support 25 the upper displacement weight.

25 The actual connections between the upper and lower displacement weights of the valve are not shown beyond the supporting rods 21 and 25, being irrelevant to the present invention. They may be in general accord with mechanism disclosed in United States Patent No. 1,190,452, granted July 11, 1916, to D. W. Patterson, for "Boiler alarm".

30 The water column chamber 10 is illustrated as being provided with a water gauge 26 shown inclined in order to be more easily read from a position below the gauge near the boiler.

35 The valve 16 may be any valve adapted to open during an abnormal height of water in the boiler and to close when the height becomes again normal. Preferably it should open automatically whenever the water becomes abnormally high, open automatically whenever the water becomes abnormally low, and shut automatically whenever the water level becomes normal.

40 The water-control valve 16 discharges into an expansion chamber 27 which has a throttled discharge into a pipe 28 and makes connection to a Bourdon pressure tube 29 so that the Bourdon tube expands and contracts responsively to the 50 rise and fall of pressure inside the expansion chamber.

45 The Bourdon tube is connected to control the opening and closing of an electric circuit 30 that contains a light or other indicator.

55 When the pressure in the expansion chamber rises, due to the opening of the valve 16, the Bourdon tube expands and by suitable mechanism closes the indicating circuit at a suitable switch, illustrated as a mercoind type of switch.

60 Obviously the Bourdon pressure tube may effect the opening and closing of the circuit in any suitable way and the mercury switch shown is intended for a conventional illustration of any switch adapted to be operated by the expansion 65 and contraction of the Bourdon tube.

65 The circuit of the indicator preferably includes a light 31 at the boiler, desirably one or more lights 32 at any desired distant point as at a board 33 for simultaneous display of the operation of a number of different boilers, and also may include an energizing coil for an electric magnet 34.

70 75 It has been found desirable to cut off the alarm after it has once sounded, and this may be ac-

complished by giving the steam in the expansion chamber 27 alternative paths of escape, through the pipe 28' to a whistle 35 or to a low pressure discharge pipe 36, and a suitable two-way valve 37 is shown for sending the steam discharge either to the alarm 35 (whistle) or to the low pressure discharge pipe 36, which preferably should connect into a heat exchanger, as for example into a low pressure heater 38.

10 Optionally the discharge from the pipe 36 may be to atmosphere.

From the expansion chamber 27 the steam escapes through a throttle orifice into the pipe 28 to the two-way valve 37, which delivers it to the 15 whistle 35 when an operating handle 39 of the valve is in low position or to the discharge pipe 36 when the handle is in raised position.

Any suitable type of two-way valve may be used and the actual structure of this valve has 20 therefore not been shown.

The operating handle 39 of the two-way valve 37 is shown weighted to make the handle normally occupy a position to send the discharging steam to the whistle, the arm being vertically 25 down and the weight being vertically below the valve stem 40 when the valve is in position to direct the steam to the whistle, and the weighted arm being horizontal, when the two-way valve is in position to direct the flow to the low pressure 30 discharge pipe 36.

When the weighted arm 39 is down the discharge, if any, is through the whistle and when the arm is swung out to a horizontal position, the escaping steam, if any, is diverted to the low 35 pressure pipe 36.

A suitable latch member 41, described in detail in the said Patent No. 1,833,630, cooperates with the electric magnet 34 to hold the weighted arm 39 up in horizontal position if it is raised into 40 horizontal position during the closure of the electric circuit 30 and is adapted to automatically release the weighted arm when the electric circuit is broken, which occurs whenever the water level becomes normal, causing the pressure in the expansion chamber 27 to fall to zero.

45 In operation, whenever the water level becomes abnormal, either abnormally high or abnormally low, the valve 16 opens.

The resultant pressure in the expansion chamber 27 simultaneously operates the alarm whistle 35 and expands the Bourdon tube 29 to close the electric circuit 30, which is shown as including a light 31 at the boiler, a light 32 at any desired 50 distant point on a display board 33 at which it is desired to disclose the operation of the boiler, and the coil of the magnet 34.

The energization of the magnet 34 permits an operator to latch the valve 37 in position to direct the escaping steam away from the whistle, as into 55 the pipe 36 to the low pressure boiler 38.

Figure 2 relates to water gauges for boilers of a type in which the water level 13' is located high above the operating floor of the boiler room and from which water gauge or water level indication or record is to be provided so that the 60 reading can be taken at the floor, or at some other point beneath the water level.

With increasing boiler pressures and with increasing sizes of the boiler unit it has become 65 more and more difficult to keep track of the height of water in the boiler from the floor of the boiler room, and in Figure 2 the condition is relieved by the use of an inclined water gauge 25' at the water level of the boiler, and by a supplemental gauge 42 at a suitable distance beneath

the water level gauge 26', the supplemental gauge 42 being operated by a displacement weight 43 that is advantageously of the type disclosed and claimed herein.

In Figure 2, a water column 10' is suitably 5 closed at the top by a bolted cap 44 and is provided with water and steam inlet connections at 11' and 12' respectively.

The upper and lower parts of the column are shown connected through passages 45 and 46 with 10 the water glass 26' shown as of the flat glass variety. The passages to the glass are controlled by valves 47 and 48 whose elements are moved through rocking levers 49 and 50 operated by 15 chains 51, 52 and 53.

The detail and even the fact of the existence 20 of a water level gauge 26' are immaterial to the operation of the rest of the mechanism and are shown to illustrate the setting in which the invention would commonly appear and the fact that 25 the gauge 42 at the floor is auxiliary to a water column rather than to a water glass.

The water column may be a main column or an auxiliary water column.

Within the water column is shown a mechanism 30 of the solid weight or displacement variety having the lower block 43 flexibly connected at 54 over pulleys at 55 with a weight 56 so that the block 43 will respond to the height of liquid within the column.

As the weight 43 rises and falls with the change 35 of water level, it affords an accurate basis for auxiliary gauge use.

The water column is connected with the lower gauge 42 by a tube or pipe 57 within which depends a flexible connection 58 which terminates in an indicating tube, rod or other gauge member 59 which is aligned with an indicator 60 so that the bottom, or the top, or any marked portion on the indicator may be read against the 40 scale 61 upon the surface of the gauge 42 adjoining the side opening 62 thereof.

The disclosure of a flat glass type of visual indicator is intended for a conventional showing for 45 any indicator operatively responsive to the vertical position of the weight 43.

The flexible connection 58 passes down through a guard 63 which may be an upward extension of tubing 57. Its effect is to insure settling of the sediment in the water within the space 64 in 50 the lower part of the water column 10'.

Various advantages accrue from trapping the sediment in the space 64. The space is so much larger in volume per unit height than is the space 55 within the water glass indicator that the sediment may be allowed to settle for a much longer time before blowing off.

The blowing off of the sediment from the space 64 through a suitable blow-off pipe 65 controlled 60 by valve 66 can be effected without materially altering the flow of water to the indicator 42 with the result that the connection 57 and the space within the indicator 42 may be maintained as a dead end, keeping the water cool in this dead end 65 of the system and hence avoiding the difficulties of glass etching of the indicator surface which results from excessive temperatures with or without excessive pressures.

As in the form illustrated in Figure 1, the effective force upon the weight 43 and weight 56 is 70 that due to the difference of water displacement while the mass moved is that corresponding to the total weight of the two members.

The less the total weight that must be moved, 75

the less will be the friction that must be overcome before the apparatus is responsive to change in water displacement.

I make the weight 43 comprise, as in the form of Figure 1, an exterior shell of metal, nonreactive with hot water and steam under the conditions of service and an interior of a light metal such as aluminum.

By making the weight of lighter material than that of iron, there is more available force obtained since for a given diameter the lighter material weight can be made deeper than the iron weight.

The external shell 67 is suitably iron, of selected composition to make it nonreactive to water and steam and the interior 68 is suitably aluminum, conveniently poured molten through an opening in the thin shell.

It will be seen that in the form of Figure 1 the water level is normally between the two opposing weights, the displacement action operating upon the lower weight in the event of abnormally low water and upon the upper weight in the event of abnormally high water, the effect of either action being to open the valve 16 that effects the sounding of an alarm or/and the giving of a visual indication of an abnormal condition.

In the form of Figure 2, the displacement variation always takes place at the lower weight 43 which is in effect a float, prevented from sinking by the counterweighting effect of the higher weight 56.

The illustrated mechanism of Figure 2 thus shows the upper member operative merely as a weight, never as a float so that the weight 56 may

be solid iron, there being no object to provide the weight 56 with an aluminum interior.

It will be evident that, by reducing the total weight of the weight, without the necessity of making it hollow, I decrease the total weight which the pulleys or other similar mechanism must bear, thus decreasing the frictional loss and increasing the sensitivity of the weight, since the weight can indicate smaller variations in liquid level.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention, what I claim as new and desire to secure by Letters Patent is:—

1. In mechanism of the character indicated, a solid weight unit including an iron shell and an interior filling therein of aluminum.
2. In a construction operating as a float, a weight having a shell of relatively heavy metal which is resistant to corrosion and a solid filling of aluminum which is less resistant to corrosion, whereby the specific gravity of the weight is less than that of the shell metal but the weight is solid throughout so as not to be subject to appreciable change in displacement in case liquid penetrates the shell, while the surface of the weight is relatively resistant to corrosion.

ALFRED L. AICHER. 35
